Edward S. Beach

ATTORNEY

UNITED STATES PATENT OFFICE.

PERY HAMMEL, OF NEW YORK, N. Y.

MECHANICAL TOY.

Application filed January 26, 1924. Serial No. 688,752.

To all whom it may concern:

Be it known that I, PERY HAMMEL, a citizen of the United States, and resident of New York city, in the county of New York and State of New York, have invented certain new and useful Improvements in a Mechanical Toy, of which the following is a specification.

This invention relates to a mechanical 10 toy.

Its object is to attract the attention of and to interest and amuse babies, as well as to benefit them.

In construction and mode of operation, 15 my new toy in its preferred form, comprises one or more ornate, contrasted color disks movable in a closed casing containing loose rattlers and having a teething ring which serves as a handle. Any suitable material 20 may be used for making embodiments of the invention, but it is preferred to make most of the structural elements out of celluloid or the like.

In the accompanying drawings forming 25 a part hereof and illustrating the invention in two different forms,

Fig. 1 is a face elevation and Fig. 2 a vertical, sectional view at line 2—2 of Fig. 31 of one form of a toy containing invention.

Fig. 3 shows a modification of what is 30 shown in Figs. 1 and 2.

In Figs. 1 and 2 of the drawings, a round box casing has its annular wall 1 fixed to a straight, tubular handle 2 which extends 35 diametrically through the annular side wall of the casing, projecting slightly at the top of the side wall and projecting from the bottom of the side wall for a distance suitable to form a handle for the casing. The 40 tubular handle passes through the annular side wall of the casing about midway between the opposite edges of the side wall. To the top end of the tubular handle the upper end of an elastic cord 3 is anchored at 45 4. The cord extends downwardly within the tube and is therein mounted in a slightly stretched condition. Within the casing of the chamber, the tubular handle, at the mid-length of that part thereof which is 50 within the chamber of the casing, is formed with diametrically opposed holes in which a transverse shaft-forming pin 5 is revolvably mounted, the ends of the shaft 5 projecting outwardly of the tube on both its sides 55 and the shaft being held in place by collars

6, one fixed on each projecting end 7. One collar bears on each side of the tube. The shaft is parallel to the opposed round, flat sides of the box casing; and preferably each shaft end has fixed to it outwardly of a 60 collar, a stiff disk 8 the outer side 9 of which is ornamented. The outward side of the ornate disk is shown parti-colored and provided with adjacent, curved white stripes 10, blue stripes 11 and red stripes 12, effecting a variety of so-called pin wheels. The visible ornamentation of the outer sides of the disks by which they are made ornate may be varied. If each end of the shaft is provided with an observable, ornate disk, 70 then both sides 13 of the box casing will be made of transparent material. If only one ornate disk is desired, then the box side opposed to the diskless end of the shaft is desirably made of non-transparent material. 75 The box sides 13 are round and as shown, each is provided with an annular flange 14 which fits tightly on a margin of the box casing side whereby the box casing is made tight. 80

Said shaft 5 extends transversely through the tube and the stretched elastic cord 3 is given a turn around the shaft within the tube 2. The under end of the stretched elastic cord is fixed at 15 to the upper end 85 of the endwise, slideable shank 16 of the handle-forming teething ring which is accessible at the lower end of the tubular handle. Said shank, round in cross-section, in the under portion of the tubular handle, is operated telescopically in relation to the handle to pull the stretched cord and twirl the pin shaft and the thereto attached disk or disks, for rocking the disks severally in one direction or the other at each up and 90 down movement of the slide. Shank 16 is held in place, against displacement, by the tension of the stretched elastic cord. The stretched cord, however, is not stretched to its full limit, but is stretched so as to be 100 taut between its upper anchored end and its attachment to the upper end of the shank within the tube. Consequently, when the shank is pulled downwardly within but not out of the tubular handle, a revoluble effect 105 is given to the disk-carrying shaft which is reversely rotated by the take up of the stretched cord on the up stroke of the teething ring carrying shank. Within the casing, shot or other rattlers 17 are placed and the 110

toy is a rattle box. The upper end of the handle tube is preferably closed by a fixed cap 18.

In Fig. 3, the shank 16 is fixed at 16^a in the handle tube and the cord instead of being anchored to the handle or otherwise, as in Figs. 1 and 2, is anchored at 18^a to the cap 18 which is a slide cap.

When parts are referred to as being fixed to other parts in the present construction, the fixation is cementitious. In each of the described forms, the upper and under ends of the cord are both fixed each to a member and the cord is concealed within the chamber of the handle and consequently is inaccessible to children using the toy, one of the members to which the cord is fixed being movable.

What I claim is:

1. As a new article of manufacture, a mechanical toy comprising in combination a casing having a transparent wall; a rockable, ornate disk within the chamber of the casing and visible through the transparent wall; a tubular handle fixed to the casing; and manually operable means partially contained within the chambers of the casing and tubular handle for rocking the disk, such means comprising a manually accessible member and also a cord anchored at its upper end adjacent the upper side of the casing and attached at its under end to the shank of an operating member telescopically mounted on the under end portion of the handle; said operating member and a disk carrying shaft revoluble within the chamber of the casing and operatively engaged by said cord.
2. As a new article of manufacture, a mechanical toy comprising in combination a casing having a transparent wall; a rock-

able, ornate disk within the chamber of the casing and visible through the transparent wall; a tubular handle fixed to the casing, extending therethrough and projecting on both sides of the casing; manually operable means partially contained within the chambers of the casing and tubular handle for rocking the disk, such means comprising a manually accessible member and also a cord connected at each end to a structural member, one of which members is a movable, operating member; said operating member and a disk-carrying-shaft revoluble within the chamber of the casing and operatively engaged by said cord.

3. As a new article of manufacture, a mechanical toy comprising in combination a casing having a transparent wall; a rockable, ornate disk within the chamber of the casing and visible through the transparent wall; a tubular handle fixed to the casing, extending therethrough and projecting on both sides of the casing; manually operable means partially contained within the chambers of the casing and tubular handle for rocking the disk, such means comprising a manually accessible member and also a cord connected at each end to a structural member, one of which members is a movable, operating member; said operating member and a disk-carrying-shaft revoluble within the chamber of the casing and operatively engaged by said cord; said casing being of box form and the disk-carrying-shaft extending through and being revoluble in opposed bearing holes through that portion of the handle which is within the casing.

Signed at New York city in the county of New York and State of New York this 31 day of December A. D. 1923.

PERRY HAMMEL.
